UNITED STATES PATENT OFFICE.

THOMAS L. LAWTON, OF PHILADELPHIA, PENNSYLVANIA, ASSIGNOR TO
THE BURLINGTON CARPET COMPANY, OF NEW JERSEY.

DESIGN FOR A RUG.

SPECIFICATION forming part of Design No. 21,905, dated October 18, 1892.

Application filed September 23, 1892. Serial No. 446,736. Term of patent 3½ years.

To all whom it may concern:

Be it known that I, THOMAS L. LAWTON, a citizen of the United States, and a resident of the city of Philadelphia, in the county of Philadelphia and State of Pennsylvania, have invented a new and original Design for Rugs, of which the following is a specification, reference being had to the accompanying drawing, which forms a part of the same.

10 The invention relates to a design to be worked into or upon surfaces, such as rugs or similar fabrics; and it consists in the novel configuration and grouping of figures herein specifically shown and claimed.

15 The accompanying drawing is a face view of a rug, showing my new design, which has the following characteristics:

A is a central figure imposed upon a sub-

stantially-plain background B, so as to form a contrast therewith, the central part of said 20 figure being formed of a bunch of flowers, buds, and foliage, and its outlines being defined by a garland of flower and leaf forms. Scroll representations and flower, bud, and leaf forms are prolonged from top and bottom 25 of the central figure toward and across both ends of the pattern.

What I claim as new, and desire to secure by Letters Patent, is—

20 The design for rugs, consisting of the de- 30 sign substantially as shown.

THOMAS L. LAWTON.
